UNITED STATES PATENT OFFICE.

JOHN TURL, OF NEW YORK, N. Y.

IMPROVEMENT IN DRIP-POTS FOR SUGAR-HOUSES.

Specification forming part of Letters Patent No. 18,215, dated September 15, 1857.

To all whom it may concern:

Be it known that I, JOHN TURL, of the city, county, and State of New York, have invented a new and useful Improvement in the Construction of Sirup or Drip Pots Used in Sugar-Refining; and I do hereby declare that the following is a full, clear, and exact description of the same, reference being had to the annexed drawings, making a part of this specification, in which—

Figure 1 is a vertical section of my improvement, taken in the line $x x$, Fig. 2. Fig. 2 is a horizontal section of the same, taken in the line $y y$, Fig. 1. Fig. 3 is a reduced perspective view of one of the halves of the pot. Fig. 4 is a vertical central section of the ordinary pot in use.

This invention relates to an improvement in the construction of pots which support the sugar-mold, and which receive the sirup or drip therefrom. Two kinds of pots have been hitherto used, one kind being formed of earthenware and the other of cast and sheet metal combined. Those constructed of earthenware have been chiefly abandoned, as they require to be made quite heavy in order to guard against breakage, and more or less loss is sustained thereby, even when made very cumbersome. The other kind, constructed of a combination of cast and sheet metal, are very liable to leak at the joint in consequence of one part of the pot—the cast-iron portion—being perfectly rigid or unyielding, and the other part—the sheet-metal portion—being allowed to yield or give.

This invention is designed to obviate the objections attending the two kinds of molds previously used—viz., the liability to break and to leak—and to produce a pot equally as light, fully as cheap, and far more durable than either of the kind mentioned.

The invention consists in constructing the pot of two parts, each part being formed of a piece of sheet metal swaged or “struck up” in proper shape so as to form a vertical half

of the pot, the two parts being connected by rivets, by brazing, or in any proper way.

In Fig. 3 a perspective view of one of the parts A is shown. These parts A A may be swaged or struck up by means of dies, or in any proper way, and the edges of the two parts may be connected by rivets a , as shown in Figs. 1 and 2; or the edges may be brazed together or secured in any proper way. A bottom, B, is secured in the pot by rivets b ; or said bottom also may be brazed. It has a flange, c, struck on its edge, by which it may be secured in the pot. The two parts A A thus connected form a light and durable pot—one sufficiently strong to support the weight of the mold, and not liable to leak in consequence of being bruised or bent.

In Fig. 4 the ordinary cast and sheet metal pot is shown. C represents a cast-iron top, and D is the sheet-metal lower portion, the two parts being connected by rivets d . The cast-iron top C is liable to break if it receives a blow or falls any distance upon a hard substance, and in case the sheet-metal portion D receives a blow it will be bent inward, as shown in red, and as the top C is unyielding or rigid the joint will be parted. By my improvement this difficulty is avoided, for if the pot is bruised the joints will not be parted, for all parts will yield or give alike.

The sheet metal of which the parts A A are made may be of any proper thickness.

Having thus described my invention, what I claim as new, and desire to secure by Letters Patent, is—

Constructing the pot of two metal parts or halves, A A, formed or struck up in proper shape by any proper means, and connected together by rivets a , by brazing, or in any suitable way, substantially as described.

JOHN TURL.
